UNITED STATES PATENT OFFICE.

EDWARD JAMES THOMAS, OF ELPHINSTONE, MANITOBA, CANADA.

CATTLE-GUARD.

956,745.

Specification of Letters Patent.

Patented May 3, 1910.

Application filed June 8, 1909. Serial No. 500,949.

To all whom it may concern:

Be it known that I, EDWARD JAMES THOMAS, of the village of Elphinstone, in the Province of Manitoba, Canada, have invented certain new and useful Improvements in Cattle-Guards, of which the following is the specification.

My invention relates to cattle guards, and the object of the invention is to provide a guard which will effectually prevent cattle or such like animals from passing along a track, such guard effecting this result without harm to the animals.

It consists essentially in a set of gates located to the side of the track and adapted to close across the track, and means for operating the gates and returning them to the inoperative position, the parts being arranged and constructed as hereinafter more particularly described.

Figure 1 is a detailed perspective view of a portion of the track showing my gates in the open position. Fig. 2 is a vertical sectional view in the plane denoted by the line X X', Fig. 3. Fig. 3 is a plan view of one of the gates showing a portion of the operating mechanism. Fig. 4 is an enlarged detailed side elevation of the pinions employed to turn the gate.

30 In the drawings like characters of reference indicate corresponding parts in each figure.

1 and 2 represent the usual track rails supported on the ties or sleepers 3.

35 4 is the usual fence post to the side of the roadway which crosses a railroad track, and 5 represents a fence.

3' and 3² are ties somewhat longer than the ties 3, such being especially provided for 40 my guard.

6 and 7 are beams between the respective ends of the ties 3' and 3² and are secured firmly to them.

8 and 9 are similar angle plates firmly secured at 10 to the beams 6 and 7, said angle plates carrying horizontally and vertically directed bearings 11 and 12 which appear directly opposite each other at either side of the track and are in alinement with the fence 50 to either side of the track.

13 is a cross shaft having its ends mounted in the horizontally directed bearings 11,

said shaft being provided with segmental bevel pinions 14 and 15 at their ends adjoining the bearings.

16, 17 and 18 are longitudinally extending boards forming a front platform, such boards being connected by cross strips 19 and 20, and being located between the tracks 1 and 2. The rear end of the platform rests on one of the cross ties 3, and the forward end is supplied with vertically extending brackets 21 which are connected pivotally to horizontal arms 22 which pass rearwardly from sleeves 23 adjustably secured to the shaft 13 by set screws 24 so that when pressure is brought to bear on the upper face of the platform its forward end will tend to pass downwardly.

25 is a rear platform appearing between the tracks and immediately behind the platform before mentioned.

26 are longitudinally extending bars secured rearwardly to the sides of the platform 25 and forwardly to the horizontally directed arms 27 which extend also from the sleeves 23 hereinbefore mentioned. It is to be noticed that the forward ends of the bars 26 are curved or bent downwardly at 26'.

28 is a cross rod secured to the under face of the forward platform by straps 29 said shaft being supplied at its ends with rollers 30 which operate within slots 31 formed in the bars 26.

33 and 34 are plates appearing at either side of the tracks 1 and 2 and directly opposite the forward platform, to which they are secured by means of bars 35 which pass beneath the rails.

36 are vertically directed shafts having 90 their lower ends rotatably received within the vertically directed bearings 12 hereinbefore mentioned. The shafts 36 have secured to their lower ends bevel pinions 37 which mesh with the segmental bevel pinions 14 and 15. The shafts 36 carry gates 38 which are adapted to open and close according as the shaft is rotated. Each gate has a portion 39 extending at right angles therefrom which is adapted to close the opening between the respective shafts 36 and the posts 4 when the gates are in the open position.

In order that the gates may be removed I have made the shafts square in cross section

and have secured straps 40 to the gates so that it is only necessary to raise the gates to remove them.

41 are springs coiled around the lower 5 ends of the shafts 36 and having their ends secured to the gates at 42 and to the beams 6 and 7 at 43, the tendency of such springs being to continuously force the gates open, that is, to bring them to the position shown 10 in Fig. 1.

The operation of the guard is as now described. When an animal passing along the track steps on the rear platform 25 it is depressed and has a tendency to turn on the 15 rollers 30 thereby raising the forward ends of the bars 26 and rotating the shaft 13 in a direction which causes the segmental pinions 14 to close the gates across the track through the operation of the gears 37. At 20 the same time the rollers are depressed and carry with them the forward platform which forces the arms 22 downwardly and assists in the action of turning the gates. In event of an animal passing across the 25 tracks and stepping on the forward platform it is depressed by the animal's weight and the gates are closed across the track, the shaft being rotated by the arms 22. In both instances as soon as the animal passes from 30 the platforms the gates are immediately thrown to the open position by the springs. In order to avoid any serious consequences in event of the gates not returning to the open position after having been closed I 35 have made the pinions 14 and 15 segmental so that they will escape from the gear wheels 37. If the gates were to be hit with a train they would turn freely as soon as the pinions 37 were freed from the pinions 14 40 and 15.

I have constructed the guard so that it can be readily taken apart and stored when it is not required, it being only necessary to slip the gates off the shafts and remove the 45 shafts from the bearings, the remaining part

of the guard being free to be removed as soon as the bolts holding the angle plates 8 and 9 are removed.

What I claim as my invention is:—

1. In a cattle guard, the combination with 50 a suitably mounted cross shaft located beneath the rails of a track, said shaft being designed to actuate an opposing set of gates to obstruct passage along the track, of a forward depressible platform adapted when depressed to rotate the shaft, and a rear depressible platform having bars extending therefrom and secured forwardly through arms with the shaft, a cross rod carried by the forward platform, and rollers located at 55 the ends of the rod and operating within slots provided in the bars, as and for the purpose specified.

2. In a cattle guard adapted to obstruct 60 passage along the track, the combination with a suitably mounted cross shaft located beneath the rails of the track, said cross shaft being adapted to operate opposing gates located to the sides of the track, of adjustable sleeves secured to the shaft and having arms extending from the opposite sides thereof, a front platform supported forwardly by brackets from one set of arms and resting rearwardly on one of the ties supporting the rails, a rear platform having 65 forwardly extending bars secured thereto, said bars having their free ends turned downwardly and pivotally secured to the remaining pair of arms, a cross rod secured to the front platform and having rollers at the 70 ends thereof, said rollers operating within slots formed in the bars, as and for the purpose specified.

Signed at Russell, in the Province of Manitoba, this sixth day of May 1909.

EDWARD JAMES THOMAS.

In the presence of—

A. R. TINGLEY,
CHARLES H. HOLBECH.
